CHARLES HENRY TOWERS, OF BALTIMORE, MARYLAND, ASSIGNOR, BY MESNE ASSIGNMENTS,
TO THE SINGER MANUFACTURING COMPANY, A CORPORATION OF NEW JERSEY.

SEWING-MACHINE THROAT-PLATE.

No. 899,574.

Specification of Letters Patent. Patented Sept. 29, 1908.

Application filed February 1, 1906. Serial No. 298,969.

To all whom it may concern:

Be it known that I, CHARLES HENRY TOWERS, a citizen of the United States, and resident of the city of Baltimore and State of Maryland, have invented certain new and useful Improvements in Sewing - Machine Throat-Plates, of which the following is a specification.

This invention relates to improvements in throat-plates for sewing machines, and has for its object to provide means to protect the material being operated upon from the action of the serrated surface of the feed-dog when, for any purpose, it is desired to manually control the length and the direction of the stitch; for example, as when it is desired to fasten off the end of the seam, to do tacking, embroidering, etc.

In the accompanying drawings illustrating the invention, in the several figures of which like parts are similarly designated, Figure 1 is a front end elevation of the bed-plate of a sewing machine provided with my improved throat-plate, together with sufficient of the cloth-feeding mechanism to show the application of my invention, and Fig. 2 is a plan view of the throat-plate.

My invention is herein illustrated in connection with the well known Wheeler & Wilson sewing machine, commercially known as No. 61 (high speed), and the description of the machine may, therefore, be limited to the novel features comprising the present invention and the parts immediately coöperating therewith.

1 is the bed-plate of the sewing machine, 2 the presser-bar, 3 the presser-foot, 4 the presser-foot screw, 5 the pintle bearing for the feed rock-shaft 6 (the latter shown in dotted lines only), 7 the pintle bearing for the feed lift rock-shaft 8 (the latter shown in dotted lines only), 9, 9, the pintle bearing set-screws, and 10 the feed-bar, one end of which is pivoted by screw 11 to a lever 12 (shown in dotted lines only), which latter, in the present instance is formed integral with the feed rock-shaft 6, the opposite end of the feed-bar 10 being connected, through a slide block (not shown) mounted upon the inner end of the stud bolt 13, with an arm 14 projecting from the feed lift rock-shaft 8, the

said stud bolt 13 and block carried by it projecting into a slot 15 formed in the end of the feed-bar 10.

16 is the hook driving shaft, shown only in section, Fig. 1, and 17 is a nut for securing the bolt 13 in the arm 14 of the feed lift rock-shaft 8.

18 is the feed-dog, secured by suitable screws, not shown, to the feed-bar 10, all of which are in construction and operation substantially the same as in the No. 61 Wheeler & Wilson sewing machine hereinbefore referred to.

19 is a throat-plate to the upper side of which is secured, by screws 20, 20, one end of a spring-plate 21, having a feed opening 22' the opposite end of said spring-plate being free to move upon, and in the direction of the length of said throat-plate, thus permitting the spring to assume the half-elliptic position shown in Fig. 1, or to be forced, by the action of the presser-foot, down upon the throat-plate, as when the sewing machine is operated for effecting an ordinary seam, it being understood that the presser-foot, when free to act, is held down upon the throat-plate by the resiliency of a suitable presser spring mounted upon the presser-bar in a manner common to sewing machines generally.

To insure that the needle hole 22, in the spring-plate 21, will be held against accidental adjustment, relatively to the needle hole 23 (shown in dotted lines, Fig. 1) in the throat-plate 19, I provide the spring-plate 21 with a rib or offset portion 24, which is secured by the screws 20, 20, in a groove 25, formed in the throat-plate.

When it is desired to fasten off a seam or to form stitches at an angle to the line of the feed, it has been the general practice to slightly raise the presser-foot and control the movements of the material by shifting it manually to the required positions, but in doing so the serrated surface of the feed-dog would come in contact with the under surface of the material, making the control of the material difficult; and to avoid this interference of the action of the feed-dog is one of the objects of my improved construction. Again, when it is desired to do embroidering, it has been the common practice to remove

the feed-dog from the feed-bar and secure the presser-foot elevated above the throat-plate a distance of substantially the thickness of the material being operated upon. My improved construction avoids the necessity of removing the feed-dog and at the same time, by restoring the presser-foot to its normal adjustment, leaves the sewing machine in condition for effecting the ordinary seam.

10 The lugs 26, 26, formed on the underside of the throat-plate for the reception of the bobbin-case stop finger, are the same as are commonly employed in the construction of Wheeler & Wilson sewing machine herein referred to. The throat-plate 19 is secured on the bed-plate 1 by the commonly employed throat-plate screws, not shown, passing

through holes 28, 28, in the spring-plate 21 and threaded into the bed-plate.

What I claim is:—

20 In a sewing machine the combination with a presser-foot, a throat-plate provided with the usual opening for the feed dog, a spring plate having a corresponding feed opening mounted on said throat-plate, and adapted to raise the material operated upon above the surface of the feed-dog, as specified.

25 Signed at the city of Baltimore, and State of Maryland, this 24th day of January A. D. 1906.

CHARLES HENRY TOWERS.
